DOOR SUPPORTING HINGE AND LOCKING
MEANS

George F. Claus, Denver, Colo.

Application February 18, 1939, Serial No. 257,243

3 Claims. (Cl. 20—16)

This invention relates to door structures and pertains particularly to improvements in mechanism for hanging or supporting the same and for locking the same.

5 The present invention has for its primary object to provide a novel and improved mechanism for hingedly supporting a door structure whereby such door structure is normally secured at each of its four vertical edges to the vertical sides of 10 a door jamb and may be released for swinging movement on a pivot adjacent any one of the said four edges by releasing the securing means at the other three edges.

Still another object of the invention is to provide in a door structure supporting means of the above described character, a novel means for locking or securing the door whereby the movement of the door is prevented even though the said securing means at any three of the four 20 edges thereof may be released.

The invention broadly contemplates the provision of a door having pairs of hinges at each of its four vertical edges which are connected with the adjacent faces of the door frame. Each co-acting pair of hinges is in two parts which are held together by a removable pintle and the pintles of each pair of hinges are connected so that they may be moved together to release the hinge halves. By removing the pintles of any three 30 pairs of hinges, the door may be swung to open position upon the remaining pair. Associated with the hinges is a shiftable supporting unit which carries means whereby it may be locked or fastened to the door, the supporting unit constituting a part of the jamb and this supporting unit must be removed from the locking means before the door can be swung upon a selected pair of hinges even though the pintles for the other three pairs of hinges may have been shifted to 40 release the hinge halves which they normally pivotally couple together.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a horizontal sectional view through a 55 door constructed in accordance with the present

invention, showing the hinge supports at the edges thereof and the locking means, this section being taken upon the line 1—1 of Fig. 2.

Fig. 2 is a view in elevation of the structure shown in Fig. 1, portions being broken away. 5

Fig. 3 is a sectional view on the line 3—3 of Fig. 2.

Fig. 4 is a vertical section on the line 4—4 of Fig. 2.

Fig. 5 illustrates in bottom plan a means for 10 preventing accidental downward movement of the pintle rods.

Referring now more particularly to the drawing, the numeral 10 designates a door in the central portion of which is an opening 11. Upon 15 each side face of the door is mounted the auxiliary door 12 which is connected to the main door by hinges 13 and covers a side of the opening 11.

The door 10 is set within the usual wall opening 14, each vertical edge of the door 10 being 20 flanked by a jamb which is indicated generally by the numeral 15.

The face of each jamb is chambered or recessed, as indicated at 16, to receive a shiftable post 17. Upon the two sides of the door or wall 25 in which the door is mounted, the jamb is provided with corner recesses 18 which open toward the door and laterally with respect thereto, these openings being provided to receive the door hinges when the door is swung to open position, 30 as hereinafter described.

At each of the four vertical edges of the door there is a hinge unit 19, which is made up of the leaves 20 and 21, which are secured respectively to the adjacent frame and the door, and each of 35 these hinge leaves has the usual knuckles which are in interdigitating relation with the knuckles of the adjacent leaf.

At each of the four vertical edges of the door, there is disposed the vertically extending hinge 40 pintle rod 22 which carries the two vertically extending laterally disposed pintles 23 which are parallel with the rod and each of which is adapted to extend upwardly through the connected or interdigitated knuckles of a pair of hinge 45 leaves, as shown in Fig. 4. At its lower end, each pintle rod has connected therewith the two oppositely directed bars 24, each of which is accessible from one side of the door.

Countersunk in a vertical edge face of the door 50 is a fixed nut 25 and opposing this nut in the adjacent movable post 17 and in the face of the post remote from the adjacent door edge is a fixed nut 26. The nut 26 of each post is concentric with a passage 27 which passes through 55

the post and is concentric with the nut 25, and this latter nut is concentric with the passage 28 in the body of the door and which leads into the area 11.

5 Threaded through each post carried nut 26 is an exteriorly threaded sleeve 29, which carries upon the end remote from the door, the knob 30.

Extending through the threaded sleeve 29 is the smooth stem 31 which forms an end continuation of a screw 32 which is threaded in the door carried nut 25. The screw 32 is of larger diameter than the stem 31 and, therefore, one end of the screw abuts the inner end of the threaded sleeve 29. This screw 32 is provided 10 with left-hand threads whereas the sleeve 29 is provided with right-hand threads.

In the opposite end of the screw 32 from the stem, there is formed the longitudinal threaded passage 33 which is adapted to receive the threaded stem portion of a lock screw 34 which is inserted from within the door opening or chamber 11. Thus it will be seen that it is necessary to open one of the auxiliary doors 12 before access 15 may be had to this locking screw 34.

25 The end of the stem 31 remote from the screw 32 extends beyond the sleeve 29 and has secured thereto the knob 35.

Located below the nut 26 in each post 17 is a flanged nut 36. Threaded into this nut is a screw 37 which has upon its outer end the head 38 which is connected therewith by the restricted neck portion 39. This neck portion 39 of the screw extends through a slot 40 in the back face or side of the jamb 15 so that upon rotation of 30 the screw through the medium of the head 38, the screw will be held against longitudinal movement and will effect the sliding or shifting of the adjacent post 17.

Extending over the rear side of the post 15 40 across the screw head 38 is a guard 41 for the screw head, which prevents lateral movement of the screw.

While the securing or locking mechanism has been shown upon one side only of the door structure, it is to be understood that such mechanism 45 may be employed at the opposite side also if found desirable. In other words, the door may be furnished with two oppositely disposed locking or securing units as well as the two oppositely disposed mechanisms for shifting the posts 17.

50 In order that the bars 24 of the pintle rods may not interfere with the shifting movement of the door upon manipulation of the screws 37, each of the jambs 15 is provided at suitable elevations with recesses 42 into which the bars may move when the door is shifted. The recesses 18 are also made relatively long so that the pintles at the ends of the bars may move thereinto under certain conditions, when the pintle rods have 55 been dropped.

In order that vibration or the weight of the 60 pintle rods themselves, will not cause the rods to shift downwardly and thus release the leaves of the hinges, a shiftable member in the form of a plate 43 is disposed upon the inner face of each post 17 directly below the ends of the rods 22, as shown in Fig. 4. This plate has the forwardly extending end ears 44 and when the plate is centrally positioned on the post 17, these ears 65 will lie below the ends of the rods 22 and thus prevent them from dropping. When the rods are to be shifted downwardly for the disengagement of the pintles from the hinges, the plate 43 lying therebeneath may be shifted in one direction transversely of the post so that the ears 70

44 will be out of alignment with the rods and then the rods may be forced downwardly by manipulating the bars 24.

From the foregoing, it will be apparent that the operation of the present door structure is 5 accomplished as follows:

First, it is necessary to open one of the auxiliary doors 12 and back out the screw 34 from the main securing screw 32. By now rotating the knob 30 by giving a clockwise turning motion to it, the right-hand threaded sleeve 29 will be moved through the post 17 away from the door. Next the knob 35 is turned in a clockwise direction so as to unscrew the left-hand threaded screw 32 from the door carried nut 25. Following this operation of releasing the securing screws, three of the four pintle carrying rods are shifted down to remove their pintles from the adjacent hinge leaves so as to disconnect such leaves, thus leaving the door suspended only 10 upon one pair of hinges. It will, of course, be understood that the door may be swung upon any selected one of the four pairs of hinges. After the disengagement of the pintles from the several 15 pairs of hinges, the post 17 which has attached thereto the leaves of the pair of hinges which have not had the pintle removed therefrom and which, therefore, have been selected for supporting the door in its swinging operation, is shifted into the adjacent jamb recess 16 by manipulating 20 the screw 37. This will separate the knuckles of the leaves of the opposite pairs of hinges and permit the free swinging movement of the door in one direction to open position. When the door has been shifted by the use of the screw 37, the 25 operating or supporting hinges will move in the adjacent jamb recesses 18, as will be readily apparent from the illustration of the structure.

What is claimed is:

1. In a structure of the character described, a 30 door frame including two vertical jamb members in each of which is formed a recess opening into the door opening, a door structure disposed in the opening between said jambs, a pair of supporting hinges at each of the four vertical edges 35 of the door, each of said hinges including a pair of leaves having interdigitating knuckles, each of said hinges having a leaf secured to the door, posts disposed vertically in said jamb recesses and adapted to be shifted therein toward or away 40 from the door, the other leaves of the adjacent pairs of hinges being secured to the post, pintles connecting the leaves of said hinges, means connecting the pintles of each adjacent pair of 45 hinges whereby such pintles may be shifted relative to the hinges to disconnect the hinge leaves, and means for shifting either of said posts into the jamb recess when the pintles of the remotely 50 related hinges have been removed whereby to separate said last hinges for free swinging of the 55 door, the other leaves of the said remote hinges being secured to the adjacent post.

2. In a structure of the character described, including a door opening having jambs each of which is provided with a longitudinally extending chamber which opens into the adjacent door opening, a post disposed vertically in each jamb chamber and being adapted to be shifted into and out of the chamber, a door in the door opening between said posts, a pair of hinges disposed one 60 above the other at each of the four vertical edges of the door, each pair of hinges having two leaves one of which is secured to the adjacent door and the other being secured to the adjacent post, a 65 rod member disposed vertically adjacent each 70

75

pair of hinges, a pair of pintles carried by each rod member and pivotally coupling the leaves of the adjacent hinges, means coupling each of said posts with the adjacent jamb facilitating shifting the post and the attached door when the pintles of the remotely related hinges have been removed to disconnect the leaves thereof, and means for securing the door to each post whereby pivotal swinging of the door upon a pair of hinges may be prevented.

5. 3. In a structure of the character described, including a door opening having jambs each of which is provided with a longitudinally extending chamber which opens into the adjacent door opening, a post disposed vertically in each jamb chamber and being adapted to be shifted into and out of the chamber, a door in the door opening between said posts, hinges disposed at each

of the four vertical edges of the door and coupling the same with the adjacent post, means for uncoupling the door at any of its edges from the adjacent post, means coupling each of said posts with the adjacent jamb facilitating shifting the post and the attached door when the door has been uncoupled from the other post, said door having a central chamber therein which is accessible from both sides of the door, an auxiliary door pivotally supported upon the main door at each side thereof and closing the adjacent side of the chamber, screw means carried by each post and extending into the adjacent edge of the door, and means disposed within the door chamber and engaging said screw for preventing the rotation of the latter.
